UNITED STATES PATENT OFFICE.

CARL POLSON, OF VERMILLION, KANSAS.

END-GATE FOR WAGONS.

1,274,325.

Specification of Letters Patent. Patented July 30, 1918.

Application filed November 10, 1917. Serial No. 201,318.

To all whom it may concern:

Be it known that I, CARL POLSON, a subject of the King of Sweden, residing at Vermillion, in the county of Marshall and State 5 of Kansas, have invented new and useful Improvements in End-Gates for Wagons, of which the following is a specification.

This invention relates to improvements in end gates for wagons and relates particularly to improvements in end gates which may be used as scoop boards when desired.

In carrying out the present invention it is my purpose to provide an end gate for wagons which may be readily and quickly applied to the wagon box and removed therefrom, and which may be swung downwardly to an inclined position and held in such position to form a scoop board to facilitate the removal of the contents of the 20 wagon box.

It is also my purpose to improve and simplify the general construction of wagon end gates and to provide an end gate wherein the component parts will be so arranged and correlated as to reduce the possibility of derangement to a minimum and which may be readily, securely, and quickly fastened in position.

With the above and other objects in view 30 the invention consists in the construction, combination and arrangement of devices hereinafter described and claimed.

The present invention is an improvement on the end gate for which Letters-Patent of 35 the United States No. 1,173,857 were granted to me February 29, 1916.

In the accompanying drawings:

Figure 1 is a rear end elevation of a wagon box equipped with an end gate constructed and arranged in accordance with my invention, and showing the end gate closed and fastened.

Fig. 2 is a plan of the same, partly in section.

Fig. 3 is a vertical sectional view of the same, on the plane indicated by the line 3-3 of Fig. 1, and showing the end gate closed and fastened.

Fig. 4 is a similar view of the same showing the end gate lowered and arranged for use as a scoop board.

Fig. 5 is a horizontal sectional view of the same on the plane indicated by the line 4-4 of Fig. 1.

Fig. 6 is a detailed perspective view of one of the hinge securing angle strips of the upper end gate section.

Fig. 7 is a detailed perspective view of one corner of the wagon bed and the main end gate section.

The wagon box 1 may be of any suitable construction. Secured to the inner faces of the side boards of the box, at the rear end thereof, are a pair of vertical guide strips 2 which are spaced apart to form vertical 65 guide ways between them.

The end gate comprises a main section 3, a detachable upper section 3^a and a supplemental section 3^b. The main section 3 is designed together with the section 3^a to close 70 the rear end of the box and is of a length to fit nicely between the side portions of the wagon box. Pivoted to the inner surface of the end gate section 3 adjacent the ends thereof are vertical angle iron securing 75 strips 4 which normally project at right-angles to the end gate and are provided on their outer sides with vertical ribs 5 arranged to engage in the ways between the strips 2 to hold said gate section 3 in position 80 at the rear end of the wagon box. These strips 4 may be turned inwardly toward the rear face of said gate section to disengage their ribs 5 from the strips 2 to release the gate section 3 so that the same 85 may be removed from the wagon box. Said section 3 is provided near its ends with horizontal slots 6 and working within said slots are levers 7 which are formed with the strips 4 and the outer ends of which project beyond said gate section. These levers when swung outwardly from the end gate turn the strips 4 inwardly to release the gate section 3 and when said levers are swung toward the outer surface of said gate section 95 the strips 4 are turned outwardly to engage the ribs in the ways between the strips 2.

Extending across the outer side of the gate section 3 are rods 8 which have slots 9 near their outer ends for engagement by 100 hooks 10 which are secured on the sides of the wagon box and project from the rear

end thereof. These rods pass through slots in the levers 7 and are provided with stop studs 11 which engage opposite sides of said levers so that the rods are loosely pivotally connected to the levers. The inner ends of the rods are arranged in over-lapping relation and have their inner ends pivotally connected as at 12, 13 to an operating bar 14 which is arranged between them. When 10 said rods are moved in one direction under the action of the bar 14 the levers will be actuated to disengage the ribs from the guide ways and move the outer ends of the rods outwardly so that they may be readily 15 disengaged from the hooks 10 and hence release said section 3. On the other hand when the bar 14 is swung in the opposite direction the rods are actuated to swing the levers and to turn the hinged strips 4 and 20 engage the ribs 5 of said strips in the spaces between the guide strips and at the same time the outer ends of the rods securely engage the hooks 10 and are fastened, thus securing the end gate section 3 in place. A 25 spring 15 has its ends attached to the rods 8 and serves by its tension to normally draw said rods toward each other to keep them in close engagement with the hooks 10. One of the rods 8 also has a keeper 16 for engagement by the free end of the bar 14, to lock the latter when in fastened position, as shown in Figs. 1 and 5.

The end gate section 3^a is provided on its inner side near its ends with angle iron strips 4^a which are secured thereto by hinge plates 6^a, said angle iron strips being hingedly connected to said plates as shown in detail in Fig. 6. The plates extend across the said gate section 3^a and in effect form 35 cleats to strengthen the same, the strips 4 being hingedly connected to the section 3 by hinge plates 6^b which are similar to the hinge plates 6^a. Said hinge plates 6^a extend a slight distance below the lower edge 40 of the section 3^a, the upper ends of sections 6^b terminating a corresponding distance short of the upper edge of the section 3 so that said hinge plates 6^a pass across the joint between said gate sections 3, 3^a, as shown in 45 Fig. 3 and hence bear against said section 3. The angle iron strip 4^a has a rib 5^a to engage between the strips 2, to secure the end gate section 3^a in closed position. The lower portions of the strips 4^a lie in the 50 angles between the sides of the strips 4 when the end gate is in closed position, as is indicated in Figs. 3, 4 and 5. Each strip 4^a is provided with a lever 17 the outer end of 55 which is turned outwardly as at 18, each 60 lever having a slot comprising a horizontal arm 19 and a vertical arm 20. Said levers work in slots 21 with which the end gate section 3^a is provided and extend rearwardly from said section. Each strip 4^a is pro-

vided near its lower end with a curved open 65 slot 21^a and the rib 5^a of each of said strips is provided with a horizontally arranged inwardly and rearwardly extending segmental arm 22 which has a correspondingly shaped slot 23. Headed studs 24, which in 70 practice may be screws, are secured to the rear strips 2 and project inwardly therefrom and operate in the slots 21^a when the end gate is lowered and arranged to form 75 a scoop board, as shown in Fig. 4, the section 3 of the end gate being provided in its ends with recesses or notches 25^a to receive and clear said headed studs when the end gate is closed, and as shown in detail in Fig. 7.

Rods 25 which are similar to the rods 8 pass slidably through the slots of the levers 17 and are provided at their outer ends with slots 26 for engagement by hooks 27 which are secured to the sides of the wagon box 85 and project rearwardly therefrom. The said rods 25 have stop studs 28 which engage opposite sides of the levers so that said rods are slidably connected to the levers. A lever bar 29 which is similar to the lever bar 90 14 is arranged between the over-lapping ends of the rods 25 and permanently pivotally connected to one of them as at 30, and detachably connected to the other by a pin 31 which also serves as a stop pin. 95

Hence the rods may be moved in either direction by said lever bar to cause the levers 17 to turn the angle strips 4^a as may be required to engage their ribs 5^a between the strips 2, to lock the section 3^a, or to disengage said ribs from between said strips, to release said section, as will be understood. 100

The upper and lower edges of the sections 3, 3^a are inclined as shown in Figs. 3 and 4 and the lower edge of the section 3^b is 105 also inclined, to bear and fit closely on the upper edge of the section 3^a.

To support the end gate in inclined position and hold the same for use as a scoop board, and as shown in Fig. 4, the pairs of 110 rods 25 are disconnected from each other and are arranged with their slotted ends engaged with the hooks 27 and their opposite ends passed through the slots of the levers 17, so that their stop studs 28 pass 115 through the vertical arms 20 of the slots 19 and their pins 31, 33 bear against the under sides of the levers 17. Thus said rods and said levers and the strips 4^a support the end gate in such position, the lower edge of the 120 section 3 bearing on the bottom of the wagon, and being supported thereby, as shown.

The supplemental gate section 3^b is provided on its front side, near the ends, with 125 side walls 34 which are arranged in line with the strips 4 and 4^a of the end gate sections 3, 3^a respectively and are cut away at

- their front sides below the section 3^b as at 35 to clear said strips 4, 4^a. The said side walls 33 extend to the bottom of the wagon body and are provided on the rear side of 5 their downward extensions with hooks 36 which engage in the slots 23 of the arms 22 of the strips 4^a so that said side walls 34 are thereby connected to said strips 4^a while permitting the latter to be freely operated.
- 10 The lower ends of said side walls extend forwardly into the rear end of the wagon box a slight distance when the end gate is arranged as a scoop board and by bearing against the side portions of the wagon box
- 15 prevent grain or the like from being spilled at the ends of the gate. The slots 23 enable the strips 4^a to be turned freely and in connection with the hooks 36 enable the section 3^b to be readily detached when this is desired.

While I have herein shown and described a preferred form of my invention, I would have it understood that changes may be made in the form, proportion and construction of the several parts, without departing from the spirit of my invention and within the scope of the appended claims.

- Having thus described my invention, I claim:
- 30 1. In combination with a wagon body having vertical strips on the inner sides of the side portions thereof, an end gate having pivotally mounted strips provided with means to engage the first-named strips to 35 secure the end gate in closed position, handles attached to the strips of the end gate, extending through openings in the end gate and rearwardly and outwardly therefrom, said handles being provided with 40 slots, and rods connected to the sides of the wagon body, extending through and movable in said slots and provided with means to engage and hold the handles in gate locking position when the rods are arranged 45 transversely of the gate, said rods coacting with said handles to support the gate when the latter is in inclined scoop board forming position.

2. In combination with a wagon body 50 having vertical strips on the inner side of the side portions thereof, an end gate having pivotally mounted strips provided with means to engage the first-named strips to secure the end gate in closed position, handles 55 attached to the strips of the end gate, extending through openings in the end gate and rearwardly and outwardly therefrom, said handles being provided with slots, and rods connected to the sides of the wagon 60 body, extending through and movable in said slots and provided with means to engage and hold the handles in gate locking position when the rods are arranged transversely of the gate, said rods coacting with

said handles to support the gate when the latter is in inclined scoop board forming position, and means to draw and lock said rods together.

3. In combination with a wagon body having vertical strips on the inner sides of its side portions, an end gate having pivotally mounted strips on its inner side provided with means to engage the first-named strips and secure the end gate in closed position, a supplemental end gate section 75 for arrangement on the end gate and having side walls arranged in line with said strips of the end gate, and means to detachably secure the side walls of said supplemental end gate section to the said strips of the 80 end gate.

4. In combination with a wagon body having vertical strips on the inner sides of its side portions, an end gate having pivotally mounted strips on its inner side provided with means to engage the first-named strips and secure the end gate in closed position, a supplemental end gate section for arrangement on the end gate and having side walls arranged in line with strips of the end gate, and means to detachably secure the side walls of said supplemental end gate section to the said strips of the end gate, and permit pivotal movement of said strips.

5. An end gate comprising separable sections each provided at the ends with pivotally mounted angle strips adapted to engage in the sides of a wagon body, the upper section having hinge plates for the said strips thereof, said hinge plates extending below said section and to bear against the lower section.

6. An end gate comprising separable sections each provided at the ends with pivotally mounted angle strips adapted to engage in the sides of a wagon body, the upper section having hinge plates for the said strips thereof, said hinge plates extending below said section and to bear against the lower section, the strips of said section 110 extending below said hinge plates.

7. An end gate comprising separable sections each provided at the ends with pivotally mounted angle strips adapted to engage in the sides of a wagon body, the upper 115 section having hinge plates for the said strips thereof, said hinge plates extending below said section and to bear against the lower section, the strips of said section extending below said hinge plates, and being 120 arranged in the angles of the pivoted strips of the lower section when said strips are in engaged position.

8. In combination with a wagon body having side walls, an end gate comprising 125 separable sections each provided at the ends with pivotally mounted angle strips adapted to engage in the sides of the wagon body, the

upper section having hinge plates for the said strips thereof, said hinge plates extending below said upper section and to bear against said lower section, the strips of said upper section extending below said hinge plates and being arranged in the angles of the pivoted strips of the lower section when

said strips are in engaged position and being also provided with curved open slots, and headed studs projecting from the side walls 10 of the wagon body and arranged to engage in said slots.

In testimony whereof I affix my signature.
CARL POLSON.
